UNITED STATES PATENT OFFICE

JOAH BROGDEN, OF MELROSE PARK, PENNSYLVANIA, ASSIGNOR TO DAVID LUPTON'S SONS COMPANY, OF PHILADELPHIA, PENNSYLVANIA, A CORPORATION OF PENNSYLVANIA

METHOD OF CONSTRUCTING METALLIC PARTITIONING

Original application filed December 28, 1926, Serial No. 157,445. Divided and this application filed July 24, 1928. Serial No. 295,034.

This invention relates to methods of constructing metallic partitioning useful in subdividing a floor area into any desired number of separate chambers or compartments 5 of different sizes.

More specifically, the present application is a division from my co-pending case filed December 28, 1926; under Serial Number 157,445; while it relates particularly to a 10 novel method of constructing partition panels in a manner conducive to mass production in standardized sizes. Hence, by proper choice of the parts from an amassed stock, a partition of any desired length and 15 height may be quickly erected without recourse to individual designing or fitting, or the use of special tools in erection.

For a clear understanding of this invention reference is had to the accompanying 20 sheet of drawings; wherein,

Fig. I is a face view of a solid single-panel partition unit constructed in accordance with the present improvements.

Fig. II is a corner detail of one of the 25 sheet metal blanks used in the construction of the solid panel shown by the preceding view.

Fig. III is a similar view showing the blank of Fig. II bent to form.

Fig. IV is a detail section, taken as indicated by the arrows IV—IV in Fig. I.

Fig. V shows a face view of a double-panel partitioning unit which may be used in conjunction with, or in lieu of, panel units 35 of the type shown by Fig. I.

Fig. VI shows the details at the region VI in Fig. V.

Fig. VII is a local section, taken as indicated by the arrows VII—VII in Figs. V and VI.

Figs. VIII and IX are perspective views showing structural details associated with the double-panel partitioning unit of Fig. V.

In accordance with this invention the solid single-panel type partitioning unit—depicted in Fig. I—is constructed from rectangular sheet metal blanks having their corners square cut as at 9, Fig. II, and diagonally incised as at 10. Each such blank

is bent along lines *x*, *y* and *z*, extending parallel to its side edges, in such manner as to define a depressed center field area A—Fig. III—and a mitered border molding with a bevel at B, a peripheral margin M parallel to the aforesaid center field area A, and a continuous laterally-extending perimetric flange F. After bending, the miter edges 10, of the border molding, are united by corner plates 11—Figs. III and IV—which are placed so as to overlap the junctures at the inside and thereupon welded or otherwise permanently secured.

To form a complete panel unit 12, I use two sections S, S' prepared as just described, and assemble them in opposed relation with their center field areas A abutting and their lateral perimetric flanges F overlapping, as shown in Fig. IV, thereupon securing them together, preferably by spot welding at different regions within the abutting and overlapping areas. The unit 12 thus formed is, obviously, extremely light in weight yet absolutely rigid and sturdy; and, in order to facilitate insertion of such units into a supporting skeleton frame-work, the square cuts 9 in the blanks—of Fig. II—are modified at 13 so as to predetermine blunt corners, as shown in Figs. I and III.

In constructing the double-panel units 14—Fig. V—I proceed, as above set forth, with the exception that the sheet metal blanks are angularly cut and incised only at adjacent corners so that, after bending, one edge remains unfinished, as shown at E in Fig. VIII. In assembling the panel components C—thus formed—to produce a full panel-face solid unit 14, I bring the unfinished edges of a pair of such components into overlapping relation, after the manner depicted in Fig. VIII, and secure them together along the overlap, either by spot welding or riveting, as most convenient. Two full face sections 14 thus constructed are then laid one over the other in opposing relation, as in the case of the single type unit of Fig. I, to bring their depressed center field areas A into abutment with their lateral flanges F in overlapping relation, and thereupon secure them together by spot welding.

2
To finish-off the units 14, batten strips 15 fashioned from sheet metal to the hollow configuration shown by Fig. IX, are placed over the central overlap joint between the components C, C at each side of the partitioning unit 14, the ends of the strips 15 being appropriately shaped to form a flush intersecting juncture with the border molding M along the top and bottom edges of the unit 14.

10 From the foregoing it is thought my invention will be well understood, while I reserve the right to make such detail changes as fairly fall within the scope of the appended claims.

15 Having thus described my invention, I claim:

1. The method of constructing partitioning panel units which comprises formation, by bending a rectangular blank of sheet metal with square-cut and diagonally-incised corners, of a panel face section characterized by an in-set center field area and a mitered perimetric molding with a continuous lateral flange, placing two such sections in opposed relation with their in-set center field areas abutting and their lateral flanges overlapping; and uniting the sections at intervals within the overlapping and abutting areas.

2. The method of constructing partitioning panel units which comprises formation, by bending from rectangular blanks of sheet metal with square-cut and diagonally-incised corners, panel face sections characterized by in-set center field areas and mitered perimetric moldings with continuous lateral flanges; uniting the molding beads at the corners of the sections by means of plates placed cross-wise of the meeting edges of the miter junctures; superposing two such face sections in opposed relation with their in-set center field areas abutting and their lateral flanges overlapping; and uniting said face sections at intervals within the overlapping and abutting areas.

3. The method of constructing double panel partitioning units which comprises formation, by bending a rectangular sheet metal blank with adjacent corners square-cut and diagonally incised, of a panel face section characterized by an in-set center field area and a mitered perimetric molding about three sides thereof; bringing the unfinished edge of such a section into overlapping relation with the corresponding edge of a similar section and securing the two sections together along the overlap to form one complete face of the unit; placing two such face components in opposed relation with their center field areas abutting and their lateral flanges overlapping, and securing them to each other at intervals within the contacting and overlapping areas; and applying pre-formed hollow battens of sheet metal to con-

ceal the overlap junctures at opposite side faces of the unit.

In testimony whereof, I have hereunto signed my name, at Philadelphia, Pennsylvania, this 19th day of July, 1928.

JOAH BROGDEN.
